UNITED STATES PATENT OFFICE

2,419,319

PORTABLE UTILITY BUILDING CORE UNIT

Joel Fletcher Lankton, Peoria, Ill.

Application April 9, 1945, Serial No. 587,304

3 Claims. (Cl. 20—2)

1

The present invention relates generally to improvements in utility units for building construction, and has reference more particularly to a new and improved transportable self-contained utility building core unit which is adapted to be prefabricated, as a factory item, in large quantities, and to be mounted bodily on a floor or other suitable support, and which centralizes the common household utilities in a compact and advantageous arrangement for convenient distribution to various fixtures, appliances and accessories.

One of the primary objects of the present invention is to provide a novel self-contained utility building core unit for supplying hot and cold water from a central location to the conventional fixtures and appliances in the service rooms of a modern household, such, for example, as a sink and dishwashing machine in the kitchen, a lavatory, toilet, shower and bathtub in the bathroom, and preferably also laundry tubs and a washing machine in the laundry, if provided, and for collecting and disposing of waste and sewage from said fixtures and appliances.

Another object is to provide a new and improved utility core unit of the foregoing character which incorporates, in addition, a heating plant for supplying and distributing heat, not only to the contiguous rooms, but also to the more remote rooms of a house or apartment, and an electrical supply and control panel for distributing electric current to the various electrical fixtures, appliances and accessories both within the unit and throughout the home, including for example the dishwashing machine, a stove and a refrigerator in the kitchen, the washing machine in the laundry, and lighting fixtures and outlet plugs in all the rooms.

A further object is to provide a novel self-contained utility unit which is adapted to service the various fixtures and appliances in the kitchen, bathroom and laundry with hot and cold water, heat and electric current, and for sewage, garbage and waste disposal, and in which these fixtures and appliances are closely arranged about the unit, so that the unit serves as a partition between these rooms, and as central nucleus about which the entire floor plan can be advantageously and economically designed.

Another object is to provide a new and improved self-contained household utility unit which conserves useful floor space, and utilizes dead space, and which permits a substantial saving in the cost of labor and building materials, and reduction in time, in the construction of the home, thereby making possible the production of inexpensive homes with all common modern conveniences.

A further object is to provide a novel self-contained household utility unit which requires a minimum number of connections to be made at

2

the time of installation of the unit and attachment of the fixtures and appliances thereto, and which, by reason of centralization of the utilities, avoids any appreciable loss of heat from the hot water system and the space heating system.

Other objects and advantages will become apparent as the description proceeds.

In the accompanying drawings,

Fig. 1 is a fragmentary side elevational view of one wall of a kitchen along which are arranged various fixtures and appliances adapted to be serviced from one side of the central utility unit.

Fig. 2 is a fragmentary side elevational view of one wall of a laundry at right-angles to the kitchen wall of Fig. 1, and along which are arranged various fixtures and appliances adapted to be serviced from another side of the unit.

Fig. 3 is a fragmentary side elevational view of one wall of a bathroom opposite the kitchen, and along which are arranged various fixtures and accessories adapted to be serviced from two other sides of the unit.

Fig. 4 is a perspective view taken substantially at the overhead ceiling, and illustrating the top of the unit assembly.

Fig. 5 is a plan view partially in intermediate horizontal section through the central utility unit, and illustrating the various kitchen, bathroom and laundry fixtures and appliances arranged about the four sides of the unit.

Fig. 6 is a perspective view of the prefabricated unsheathed central utility unit taken diagonally from two sides.

Fig. 7 is a view similar to Fig. 6 but taken diagonally from the two opposite sides, and with the space heater removed.

Fig. 8 is a fragmentary vertical sectional view of the enclosed central unit taken substantially along line 8—8 of Fig. 5, and illustrating the interior elements.

Fig. 9 is a plan section at substantially ceiling height of a simple room arrangement illustrating one typical adaptation of the central utility unit.

Fig. 10 is a plan section of the same room arrangement illustrated in Fig. 9, with the addition of another room.

Fig. 11 is a horizontal sectional view of a modified form of the building core unit assembly.

Referring more particularly to the drawings, the present household utility unit, which constitutes the exemplary embodiment of the invention, comprises generally a hollow upright skeleton frame structure 1 (see Figs. 6, 7 and 8) housing and supporting, in assembly therewith, a water heater 2, a space heater 3, an electrical distribution panel 4, and various pipe and duct manifolds or systems and electrical leads. In the specific form shown, these manifolds or pipe

systems comprise a cold water pipe manifold 5, a hot water pipe manifold 6, a drain and sewage manifold 7, a heating duct manifold 8, a ventilating duct manifold 9, and a gas supply pipe or manifold 10. All of these elements are closely and compactly coordinated and interrelated mostly within the confines of the frame structure 1.

The utility unit is adapted to be prefabricated, in factory production, as a transportable commercial item, with substantially all of the internal piping or plumbing and electrical leads, and preferably, but not necessarily, all of the operating equipment or service fixtures, fully installed in the frame structure 1. Thus, the unit, with the assembled or integrated supply, soil and vent piping system therein, is ready for installation in the construction of a new home, or the rehabilitation of an old dwelling. As a consequence, the unit can be produced economically in large quantities. Within the unit, the cold water manifold 5 is connected to supply water under pressure to the heater 2, and the hot water manifold 6 is connected to receive hot water from the heater 2. The heaters 2 and 3 may be heated by any suitable means. In the present instance, the water heater 2 is heated by electrical energy and the space heater 3 is fuel-fired and hence connected to receive gas or oil from the manifold 10, and provided with a suitable flue outlet for the products of combustion. If the water heater 2 were to be fuel-fired, it would be connected to the manifold 10, and if the space heater 3 were to be heated electrically it would be connected through automatic control circuits to the electrical panel 4.

Because of the complete and self-contained character of the unit, which in one sense constitutes a compact household power plant, its installation requires very few external connections, and can be quickly and inexpensively effected. Thus, for the unit itself, it is necessary after location only to connect the cold water manifold 5 to a main water pipe 5^a leading from a suitable source, such as a municipal water system, to connect the electrical panel 4 to a supply main 4^a leading from an outside source of current, to connect the main trunk of the soil manifold 7 to a vent stack 11 and to a sewer pipe 7^a, to connect the gas pipe 10 to a fuel supply pipe 10^a, and to connect the flue outlet of the heater 3 to a smoke stack 13.

It will be understood that in constructing the home, the water, sewer and gas mains 5^a, 7^a and 10^a are arranged to open at the desired location according to a predetermined pattern, and preferably, though not necessarily, to open through the supporting foundation or floor, and the lower ends of the manifolds 5, 7 and 10, to be connected therewith, are similarly arranged within the unit. The pattern may be conveniently and accurately laid out by the use of a floor templet (not shown). To install the unit, it is merely placed on the support at the desired location in registration with the pipe pattern, and then the three aforesaid base connections are made. A correlated rearrangement of the electrical supply cable 4^a, vent stack 11 and smoke stack 13 is made to facilitate connection thereof at the top of the unit with the panel 4, soil pipe 7 and flue outlet of the heater 3.

The manifolds, integrally incorporated as part of the unit, are suitably arranged with branch conduits having terminal outlets or couplings readily accessible for connection with various household fixtures, appliances and accessories.

Preferably, these outlets of the manifolds extend substantially to and terminate at the outer surfaces of the unit, for example at the top and bottom and side walls of the structural frame. After installation of the utility unit, the items of equipment to be serviced thereby may be mounted closely contiguous to and in some instances actually on the unit, and connection thereof from outside the unit with the contiguous ends of the appropriate branches or conduits of the manifolds may be speedily made.

It will be evident that when the present utility unit is employed, much of the plumbing that is ordinarily required to be made in constructing a home with separate conventional water, heating and sewer systems, with their intricate maze and long runs of pipes, is not necessary, or has been already completed at the factory at low cost. The remaining few connections required to install the unit and the fixtures can be made in a very short time. As a result, labor costs are considerably reduced, and the progress of building construction is not impeded, but is accelerated to facilitate early completion.

The self-contained portable utility unit may be made in any suitable shape, but preferably is rectangular with right-angled corners and outlined by the frame structure 1. This square-cornered form provides four side walls of which the adjacent walls are perpendicular to each other and about which the items to be serviced may be conveniently arranged in a compact central group. With the serviced items so arranged, the sides of the unit may be sheathed with wall panels 14, 15, 16 and 17 to close the frame structure 1, and is admirably adapted to constitute all or part of the partition between, and thus constitute the inner backing of the contiguous walls of, two, three or more rooms, passages or alcoves arranged in adjoining relation about the side walls of the structural frame. In general, the unit permits of economical and flexible room layouts, especially suited for low-priced homes.

An illustrative simple floor plan is shown in Fig. 9, in which the utility unit 18 defines the partition between a kitchen 19 and a bathroom 20, and one side of a connecting passageway 21, serving also as a laundry. A living room 22 opens from the kitchen 19. A plenum chamber 21^a extends along the ceiling of the passageway 21 to receive heat from the duct 8 for distribution through a grill 21^b to the living room 22. Such arrangement lends itself to expansion, with convenient utilization of the utility unit 18, as illustrated in Fig. 10, wherein a bedroom 23 is added next to the bathroom 20, and connected to one end of the passageway 21. In this instance, the plenum chamber 21^a is connected through another grill 21^c to the bedroom 23.

Various types of equipment items may, of course, be provided and the invention is not necessarily limited to the specific selection and arrangement of all of the items shown in the drawings. Of particular advantage is location of the unit as a partition (see Fig. 5) between the kitchen 19 and bathroom 20. On the kitchen side along the wall panel 14 of the unit (see Fig. 1) are located a dishwasher 24, a sink 25, a stove 26 and an electric refrigerator 27. In the present instance, the dishwasher 24, sink 25 and stove 26 are built into a floor cabinet 28. On the bathroom side, along the wall panel 15 of the unit 18, are mounted a lavatory 29 and a toilet 30. A bathtub 31 is positioned on the floor, with the foot end extending between an outside wall

32 of the bathroom 20 and the adjacent wall panel 16 of the unit 18, and the space over the tub constitutes a shower stall 33 served by an overhead shower spray 34 and adapted to be closed by a door 35. On the laundry side of the unit, along the wall panel 17, are located a clothes washing machine 36 and twin laundry tubs 37 enclosed in a floor cabinet 38. The overhead space in the kitchen 20 and laundry 21 over the cabinets 28 and 38 may be utilized for wall cabinets 39 and 40 suspended from the sides of the utility unit 18. In the foregoing arrangement, the central utility unit 18 is located in effect in a well or shaft accessible from all sides, and constitutes, with the fixtures and appliances arranged thereabout, a unitary household assembly or building construction providing substantially all of the service facilities commonly desired in a modern home.

In the preferred form, the unitary frame structure 1 comprises rectangular top and bottom frames 41 and 42 rigidly interconnected at the corners and other spaced points by vertical uprights to form an external skeleton framework. More particularly, the top frame section 41 is constructed of side members 43 and 44 and end members 45 and 46, and the bottom frame section 42 similarly is constructed of side members 47 and 48 and end members 49 and 50, these various members preferably being channel-shaped and opening inwardly.

The vertical uprights comprise four corner frame members 51, 52, 53 and 54 interconnecting the respective corners of the top and bottom frames 41 and 42, and a series of spaced intermediate frame members interconnecting the side and end members of the frames. In the present instance, there are two intermediate members 55 and 56 between the side members 44 and 48, one intermediate member 57 between the side members 43 and 47, and one intermediate member 58 between the end members 45 and 49. Preferably, the corner members 51 to 54 are angle bars and the intermediate members 55 to 59 are channel bars and all are arranged to open inwardly.

The various upright frame members are provided in such numbers and are so spaced and arranged as to impart adequate strength and rigidity to the frame structure 1, to afford support for certain utilities or service fixtures located within the unit and for certain household devices or fixtures adapted to be mounted on the exterior of the unit, and to permit ready access to the interior for purposes of installation, service and repair. In furtherance of these ends, the frame structure 1 is also provided with suitable reinforcing cross members. Thus, the bottom frame 42, which constitutes the base of the structure and is adapted to be mounted directly on a suitable foundation 60, such as a floor or other support, has a channel-shaped cross member 61 extending between and connected at opposite ends to intermediate portions of the side members 47 and 48. Similarly, horizontal channel-shaped cross members 62, 63 and 64 extend in a common plane respectively between the upright members 54 and 58, 52 and 53, and 53 and 57, and another member 65 extends in a slightly higher plane between the members 51 and 58. Likewise, three vertically spaced angle-shaped cross members or bars 66, 67 and 68 connect the upright members 52 and 56, and two similar cross members 69 and 70 connect the members 51 and 56.

The various structural elements 43 to 70 may

be made of any suitable material, such as steel, having the desired strength and rigidity, and may be rigidly interconnected in any suitable manner, as for example by welding, to constitute a prefabricated sub-assembly or framework.

It is to be understood that, within the broad aspects of the invention, the frame structure 1 is not necessarily limited to the specific shape and construction shown, but may be of any suitable skeleton form defining an internal chamber providing substantial interior space in which the basic service fixtures or utilities and pipe manifolds are adapted to be arranged and supported in a centralized and standardized manner for coupling connections to the outside fixtures and appliances. It will be evident that the major portion of the manifolds of the assembled supply, soil and venting pipe system is located substantially within the lower portion of the interior space and adjacent the bottom frame section and certain of the side walls of the structural frame 1 to provide an unobstructed space for the reception of the service fixtures, such, for example, as the hot water heater 2 and the space heater 3.

The hot water heater 2 may be of any suitable type, and in the present instance is self-contained and, hence, comprises a cylindrical water drum and suitable electrical heating means (not shown). The cold and hot water manifolds 5 and 6 open through the top end of the heater 2 to the interior of the water compartment. Preferably, the heater 2 is supported in an elevated position on a braced corner shelf 73 constructed of channel bars rigidly connected to the upright frame members 51, 55 and 58, and is additionally secured in place by an encircling strap 73a anchored to the member 58.

The space heater 3 also may be of any suitable type and shape, utilizing either gas, oil, coal, or electric current as the source of heat. In the present instance, the heater 3 consists of a rectangular hot air, gas-fired furnace having a burner (not shown) connected to the gas manifold 10, and having a flue 75 for discharging the products of combustion, and a hot air outlet connected to the trunk of the heating duct manifold 8. The furnace 3 is supported in elevated position on a platform 76 rigid with the frame structure 1 and preferably consisting of a rectangular frame constructed of channel bars resting on the cross members 63 and 64. The inner corner of the frame 76 is supported from the cross member 61 by an upright angle bar constituting the leg 77.

By supporting both of the heaters 2 and 3 in elevated position and within opposite sides of the interior chamber of the frame structure 1, the upper space in the chamber is efficiently utilized, and the lower space thereof is available for housing most of the various pipe manifolds and is readily accessible to permit entry for maintenance and repair. Such entry may be conveniently had through a door 79 in the wall panel 16 over the bathtub 31 and to one side of the hot water heater 2. The use of gas, oil or electric current as the source of heat is advantageous in that it obviates the necessity of providing convenient access for hand-firing and ash removal, and thus permits arrangement of various fixtures and appliances along all four sides of the unit.

Considering now the various pipe manifolds, the main trunk of the cold water manifold 5 is adapted to be connected to the water supply pipe 5a by a separable coupling 80 and is suitably

supported by the cross member 61 and the platform 76. One branch of the manifold has a terminal coupling 81 adapted for connection through the wall panel 15 with the water inlet of the toilet 30. Another branch of the manifold 5 leads to a set of mixing valves 82 mounted on the cross member 65 and adapted for connection to a water spout 83 discharging into the bathtub 31, and thence to a mixing valve 84 having an outlet pipe 85 adapted for connection through the wall panel 16 to the shower spray head 34. Various other branches of the manifold 5 have terminals 86, 87 and 88 suitably threaded or provided with couplings for connection respectively with the lavatory 29 and the laundry and kitchen fixtures and appliances.

Similarly, the hot water manifold 6 is connected to the mixing valves 82, and has various branches with terminals 89, 90 and 91 suitably threaded or provided with couplings for connection respectively with the lavatory 29 and the laundry and kitchen fixtures and appliances. It will be evident that the various branches of the water manifolds 5 and 6 extend through the interior of the unit to all four sides of the frame structure 1, and that they are supported in position ready for attachment thereto of the outside fixtures and appliances utilizing cold and hot water. Connection thereof with various interior elements, such as the hot water heater 2 and the valves 82, affords support for the manifolds 5 and 6. For additional support, the manifolds may be connected or strapped by suitable tie means to or rest on various contiguous members of the frame structure 1.

The drain and sewage manifold 1 comprises a main vertical soil pipe 92 which is adapted to be connected at the lower end by a coupling 93 to the sewer pipe 7^a and at the upper end by a coupling 94 to the vent stack 11, and which is supported in position by a plurality of brackets or ties 95 anchored to the frame structure. One branch of the pipe 92 has a terminal 96 suitably threaded for connection to the waste outlet of the toilet 30. A drain pipe 97, opening to one side of the soil pipe 92, rests on the cross members 61, and has various branch terminals 98, 99, 100 and 101, suitably threaded or provided with couplings, for attachment respectively with the drain outlets of the bathtub 31, the lavatory 29, and various laundry and kitchen fixtures and appliances. Thus, the terminal 98 is connected through a conventional trap to the bottom drain 102 and the overflow 103 of the bathtub 31; the terminal 100 is connected through a branched pipe 104 to the bottom drains of the clothes washing machine 36 and the laundry tubs 37; and the terminal 101 is connected to the bottom drains of the sink 25 and the dishwashing machine 24. A vent pipe 105 opens from the drain pipe 97 to the soil pipe 92 to permit the escape of sewer gases.

The electrical distribution panel 4 is conveniently supported between the cross bars 66 and 67 and has a series of conduits 106 extending downwardly therefrom to service the unit 18, and another series of conduits 107 extending upwardly therefrom and adapted to be connected to outside circuits for servicing the rest of the house. For example, the conduits 106 are connected to various outlet boxes mounted in the frame structure, including boxes 108, 109 and 110 for servicing the electric refrigerator 27 and stove 26, the dishwashing machine 24 and the clothes washing machine 36, and including an

outlet box 111 for servicing two side lights 112 for a medicine cabinet 113 mounted between the cross bars 69 and 70 above the lavatory 29 and having a mirror door 114 opening to the bathroom 20.

The top of the frame structure 1 is closed by a wall panel 115 having a central opening 116 closed by a removable cover 117. The panel 115 is located a distance from the room ceiling 118 to provide a narrow overhead space 119 which houses the heating and ventilating ducts 8 and 9, and which is adapted to be closed by a border trim 120. The heating duct manifold 8 comprises a central plenum chamber which has various branches opening through the trim-work 120 respectively to the kitchen 19, bathroom 20 and plenum chamber 21^a over the laundry 21. Suitable grills 121 and 123 are secured in the outlets to the kitchen and bathroom.

20 The ventilating duct 9 has a grill 126 in the trim-work 120 opening from the kitchen 19 and is connected to one compartment 127 of a partitioned flue box 128 adapted for connection to the chimney 13. An exhaust fan (not shown) may be mounted at a suitable location in the duct 9. The flue 75 from the heater 3 opens to another compartment 129 of the box 128 and a ventilating duct 72 opens from the interior of the unit 18 to a third compartment 130. If the water heater 2 were of the fuel-fired type, the duct 72 would be available for connection as a flue outlet from the heater combustion chamber. The chimney 13 preferably is also partitioned into three flue passages for connection respectively to the compartments 127, 129 and 130 so as to prevent back drafts. Cold air grills 131 in the base of the wall panels 14 and 17 (see Figs. 1 and 2) admit air to the interior of the unit 18 for ventilation and for supporting combustion in the heater 3.

40 Fig. 11 shows a modified form of utility unit 18^a which is similar in substantially all respects to the unit disclosed in Figs. 1 to 10, with the exception that a coal burning space heater 3^a is employed. In this instance, laundry fixtures and appliances are dispensed with, so that the wall panel 17^a is exposed and provided with a firing door 132 for introducing coal and a door (not shown) for removing ashes. Other corresponding parts are identified by the same reference numerals plus the letter ^a.

50 It will be seen that I have provided a new and improved building core utility unit which lends itself to an advantageous and economical method of building construction. The unit 18, with water and space heaters and plumbing connections, is economically prefabricated, and is adapted to be transported and installed at a central location on a floor especially prepared for it. The unit may be inserted through an opening in the outer wall 32 of the building before the wall is completed, and in fact may be constructed so compactly that it will pass an ordinary doorway. After being located in position, the unit 18 is attached to the service mains. Then, the frame structure 1 is sheathed with the wall panels 14 to 17 and 115 at the sides and top. Thereafter, the various kitchen, bathroom and laundry fixtures are arranged about the four sides in a compact and convenient assembly and attached to the appropriate terminals of the plumbing within the unit. The heating and ventilating ducts 8 and 9 are now properly arranged, and the space 119 overhead the unit is closed by the trim-work 120. The remaining rooms of the home are conveniently arranged about the centralized assem-

bly of household facilities thus provided. The building construction disclosed herein is an improvement of the construction disclosed in my copending application, Serial No. 556,222, filed September 28, 1944.

I claim as my invention:

1. A pre-fabricated portable structural utility building core unit comprising, in combination, an upright, rigid, outer structural frame having horizontal rectangular top and bottom frame sections interconnected by vertical corner and intermediate frame members defining four vertical side walls providing substantial interior space, an assembled supply, soil and vent piping system including manifolds disposed within said interior space, the major portion of said manifolds being located substantially within the lower portion of said interior space and adjacent said bottom frame section and certain of said side walls to provide an unobstructed space for the reception of service fixtures, tie means rigidly attaching said piping system at spaced points in supported relation to contiguous frame members of said side walls, certain structural members of said frame presenting means for supporting said service fixtures when inserted in said unobstructed space, said piping system having conduits extending contiguous to the bottom of said frame for attachment to external service mains, and having other conduits extending from within said frame contiguous to a plurality of said side walls for attachment from outside to household devices and fixtures to be arranged in externally spaced relationship therealong.

2. A pre-fabricated portable structural utility building core unit comprising, in combination, an upright, rigid, outer structural frame having horizontal rectangular top and bottom frame sections interconnected by vertical corner and intermediate frame members defining four vertical side walls providing substantial interior space, an assembled supply, soil and vent piping system including manifolds disposed within said interior space, one of said manifolds comprising a vertical soil pipe located closely adjacent one side wall and in remote relation to the opposed side wall of said frame, and the major portion of said manifolds being located substantially in the lower end portion of said interior space and adjacent the bottom and sides thereof to provide an unobstructed space for the reception of service fixtures, tie means rigidly attaching said soil pipe at spaced points to frame members of said one side wall, additional tie means rigidly attaching said piping system at spaced points in supported relation to contiguous frame members of said side walls, certain structural members of said frame presenting means for supporting said service fixtures when inserted in said unobstructed space, said piping system having conduits extending contiguous to the bottom of said frame for attachment to external service mains, and having other conduits extending from within said frame contiguous to a plurality of said side walls for attachment from outside to household devices and fixtures to be arranged in externally spaced relationship therealong.

3. A pre-fabricated portable structural utility building core unit comprising, in combination, an upright, rigid, outer structural frame having horizontal rectangular top and bottom frame sections interconnected by vertical corner and intermediate frame members defining four vertical side walls providing substantial interior space, an assembled supply, soil and vent piping system

including manifolds disposed within said interior space, one of said manifolds comprising a vertical soil pipe located closely adjacent one side wall and in remote relation to the opposed side wall of said frame, and the major portion of said manifolds being located substantially in the lower end portion of said interior space and adjacent the bottom and sides thereof to provide an unobstructed space for the reception of service fixtures, tie means rigidly attaching said soil pipe at spaced points to frame members of said one side wall, additional tie means rigidly attaching said piping system at spaced points in supported relation to contiguous frame members of said side walls, certain structural members of said frame presenting means for supporting said service fixtures when inserted in said unobstructed space, the compact integrated piping system forming with said frame a central core to constitute the inner backing of the contiguous walls of a plurality of rooms, passages, or alcoves arranged in adjoining relation about three of said side walls, said piping system having conduits terminating contiguous to said top and bottom sections of said frame for attachment to external service mains, and having other conduits terminating contiguous to said three side walls for attachment from outside to household devices and fixtures to be arranged in spaced relation externally along said three side walls.
